M. KOTUN,
PORTABLE TABLE AND CHAIR,
APPLICATION FILED DEC. 7, 1920.

1,380,153.

Patented May 31, 1921.

UNITED STATES PATENT OFFICE.

MICHAEL KOTUN, OF NEW GENEVA, PENNSYLVANIA.

PORTABLE TABLE AND CHAIR.

1,380,153.

Specification of Letters Patent. Patented May 31, 1921.

Application filed December 7, 1920. Serial No. 428,830.

To all whom it may concern:

Be it known that I, MICHAEL KOTUN, citizen of Czecho-Slovakia, residing at New Geneva, in the county of Fayette and State 5 of Pennsylvania, have invented certain new and useful Improvements in Portable Tables and Chairs, of which the following is a specification.

This invention relates to a portable collapsible table, with which may be combined a collapsible stool, the table being designed more particularly for the use of campers, automobilists or the like, although not limited to any particular use.

15 The invention has for an object to provide a portable collapsible table capable of being folded or collapsed into a very small package when not in use, a further object being to provide a simple construction facilitating 20 the collapsing and setting up of the table.

For further comprehension of the invention, and of the objects and advantages thereof, reference will be had to the following description and accompanying drawings, and to the appended claims in which the various novel features of the invention 25 are more particularly set forth.

Figure 1 of the drawings is an axial vertical sectional view showing my improved 30 table and chair in set up position.

Fig. 2 is a similar view, but showing the table collapsed.

Fig. 3 is a horizontal section on the line 3—3 of Fig. 1.

35 Fig. 4 is a detail horizontal section on the line 4—4 of Fig. 1.

Fig. 5 is a detail horizontal section on the line 5—5 of Fig. 1.

As here shown my improved table comprises a main tubular pedestal of telescopic 40 construction and comprising a lower tubular section 10, and an upper tubular section 11 slidable therein. The lower section 10 is preferably closed at its lower end as at 12 and externally screw threaded at upper and 45 lower ends as at 13 and 14 whereby a cap 15 may be screwed on either end as desired. This cap forms the base of the pedestal when the table is set up and forms a cover 50 for the collapsed elements inclosed in the section 10 when the table is in collapsed position.

Fixed on the section 10, about midway between opposite ends thereof, is a collar 17 55 to which are hinged at their upper ends as at 18 a series of radially arranged bracing

legs or struts 19 whose lower ends may be pointed to project into the ground.

Projecting from the upper and inner section 11 near the lower end thereof is a pin 60 20 which projects into a bayonet slot 21 in the lower section the main length of which extends vertically in the section 10 with a short lateral offset at the upper end.

Slidably held in the tube section 11 is a 65 cylindrical head 22 from the side of which a headed pin 23 projects through a bayonet slot 24 in the section 11, the main length of this slot extending vertically, with a short lateral offset at the upper end. A second 70 vertical slot 24' is formed in the wall of the section 10 to accommodate this pin 23 when the parts are collapsed. Secured at one end to the head 22 and at its opposite end to the closed bottom of the section 11 is a coiled 75 tension spring 22' which normally tends to draw the head into the section.

Hinged at their inner ends as at 25 to the top of the head 22 are a series of radially arranged arms 26, preferably formed of 80 wires or rods whose outer ends are curled around downwardly and inwardly as at 27. The inner ends of these arms are supported by the top of the section 11 and the slot 24 in the latter and the pin 23 on the head 22 85 may be arranged so as to allow the head to project a sufficient distance above the section for this purpose before the pin strikes the top of the slot, complete withdrawal of the head from the section 11 being prevented, as 90 will be apparent.

The outer ends of the arms 26 are supported by a series of radially arranged struts or braces 28 which are hinged at their lower inner ends as at 29 to the section 10 and 95 whose outer ends are forked, as indicated at 30 in Fig. 4, and adapted to engage in the crotched seat formed by the bent in ends 27 of the arms 26. To these arms is secured a canvas or other fabric 31 which forms the 100 table top.

In combining the seat or stool with the table a strut 35 is hinged as at 36 to the cap 15 and has a fabric seat element 37 fixed to its outer end, this seat element 105 being also fixed upon the upper ends of additional struts 38 having pointed lower ends adapted to take into the ground. These struts 35 and 38 cross each other and are held in this position by a ring 39 which 110 freely surrounds them at the point of crossing. Pivotaly connected at one end to

this ring is a rod 40 having a hook 41 at its opposite end adapted to engage in a recess in the collar 17 on the section 10.

Assuming the parts in the collapsed position shown in Fig. 2, the pin 20 will be at the lower end of the bayonet slot 21, and the pin 23 at the lower end of the bayonet slot 24. The cap 15 is unscrewed and placed on the bottom of section 10, and the struts 19 swung to engage the ground. By pushing against pin 23 the arms 26 and table top 31 are moved out of section 11 and the latter can then be pulled out of section 10. When the pins 20 and 23 reach the end 15 of their respective slots the section 10 and head 22 are partially turned to bring the pins into the lateral offsets of the slots thus holding the parts extended. The arms are then swung outwardly to a horizontal position and the struts engage therewith. To set up the stool 37 the strut 35 is swung outwardly and the struts 38 engaged with the ground, while the hooked end 41 of rod 40 is engaged with the recess in the collar 17. In collapsing the table the above operations will be reversed, the section 11, arms 26, and top 31 being contained within the section 10, while the remaining parts are swung to lie thereagainst.

Having thus described my invention what I claim as new and desire to protect by Letters Patent of the United States is as follows:

1. In a collapsible table, a tubular pedestal comprising a lower outer section and an upper inner telescopic section, said lower section being formed with a bayonet slot comprising a long vertical arm, and a short arm at its upper end, a pin on said upper section near the lower end thereof, said upper section being also formed with a bayonet slot comprising a long vertical arm, and a short vertical arm at its upper end, a head slideable in the upper section, a pin

on said head engaging in the last mentioned slot, and a series of arms hinged to said head and adapted to support a table top, and a coiled tension spring normally urging said head into said upper section.

2. In a collapsible table, a tubular pedestal comprising a lower outer section and an upper inner telescopic section, said lower section being formed with a bayonet slot comprising a long vertical arm, and a short arm at its upper end, a pin on said upper section near the lower end thereof, said upper section being also formed with a bayonet slot comprising a long vertical arm, and a short vertical arm at its upper end, a head slideable in the upper section, a pin on said head engaging in the last mentioned slot, and a series of arms hinged to said head and adapted to support a table top, and a series of struts hinged to the lower section and adapted to support the outer ends of the said arms.

3. In a collapsible table, a tubular pedestal comprising a lower outer section and an upper inner telescopic section, said lower section being formed with a bayonet slot comprising a long vertical arm, and a short arm at its upper end, a pin on said upper section near the lower end thereof, said upper section being also formed with a bayonet slot comprising a long vertical arm, and a short vertical arm at its upper end, a head slideable in the upper section, a pin on said head engaging in the last mentioned slot, and a series of arms hinged to said head and adapted to support a table top, and a series of struts hinged to the lower section and adapted to support the outer ends of the said arms, and a series of struts hinged to the lower section and adapted to engage the surface on which the table is resting.

In testimony whereof I have affixed my signature.

MICHAEL KOTUN.
